UNITED STATES PATENT OFFICE.

OSCAR BERNHARD HELLSTROM, OF NEUTRAL BAY, SYDNEY, NEW SOUTH WALES,
AUSTRALIA.

TROUSERS-STRETCHER.

1,377,580.

Specification of Letters Patent.

Patented May 10, 1921.

Application filed October 21, 1920. Serial No. 418,536.

To all whom it may concern:

Be it known that I, OSCAR BERNHARD HELLSTROM, a subject of the King of Great Britain, residing at Neutral Bay, Sydney, in 5 the State of New South Wales, Commonwealth of Australia, have invented certain new and useful Improvements in Trousers-Stretchers, of which the following is a specification.

10 This invention relates to improvements in trousers stretchers adapted to be readily applied to chairs, wardrobes, or other convenient furniture or fixture.

To the back of the chair or other approximately straight piece of furniture or fixture is attached two oppositely positioned brackets provided with guides or slots in which pins on the ends of a transverse bar are capable of sliding enabling said bar to partially 20 rotate. The inner side of said bar is beveled so that when one end of the trousers, usually the waist end, is placed between the bar and the rail of the chair or other straight fixed piece of furniture or the like it is wedged 25 tightly therein on partially rotating the bar.

On one of the bottom rails of the chair or other suitable article of furniture is or are hinged or pivoted one or two clamps whose free ends extend upwardly. The opposite 30 end of the trousers is then drawn tightly by hand to stretch the garment and is inserted between said clamp or clamps and vertical slats or boards on the chair or other suitable furniture fixture. Through a slot in each 35 clamp passes a short arm fixed to the corresponding vertical slat and on said arm is pivoted a cam lever which on being operated forces the clamp toward its corresponding vertical slat and securely retains the end of 40 the stretched trousers.

In the accompanying drawings,

Figure 1 is a perspective view illustrating the invention as applied to a chair.

Fig. 2 is a sectional elevation showing 45 clamp compressed against its corresponding seat, while

Fig. 3 is a similar view showing the clamp in the released position.

Fig. 4 is a part sectional elevation illustrating the invention applied to the wall or 50 door of a wardrobe or other piece of furniture.

In Figs. 1 to 3, the brackets 5 and 6 are preferably made integral with the respective members 7 and 8 of the chair back. These 55 brackets however may be secured by screws or the like. In the brackets are the opposite slots or guides 9 and 10 in which slide the pins 11 and 12 on the transverse bar 13 having a bevel edge 14 which bar is capable of 60 partial rotation on its pins 11 and 12. To the seat or seat rail 15 and to the rail 16 are rigidly secured one or more vertical slats or 65 boards 17 to which are hinged clamps 18 provided with slots 19. A metal or other arm 20 is secured to each slat and passed through the slot 19 in its respective clamp. On each of said arms is a pivoted cam 21 provided with an operating handle 22.

In Fig. 4, 23 is the wall or other straight 70 piece of furniture or fixture, each bracket being affixed by screws 24 or other fastenings. In this case slats may be dispensed with, each clamp 18 being hinged to the wall 23 to which also is secured each of the arms 20. 75

I claim:—

In combination with a supporting element, brackets thereon, a transverse bar mounted in the brackets for vertical sliding movement and also for partial rotation, said bar being 80 adapted to hold one end of a pair of trousers, a plurality of clamps adapted to hold the opposite end of the trousers, said clamps being each hinged at its lower end to said supporting element for vertical swinging movement 85 and having a vertical slot, arms projecting from the supporting element through said slots, and cams pivotally mounted on said arms and bearing against the outer sides of the said clamps. 90

In testimony whereof I have hereunto set my hand.

OSCAR BERNHARD HELLSTROM.
